UNITED STATES PATENT OFFICE

1,934,776

MACHINE FOR PRINTING WEBS

Max Stoessel, Ridgewood, N. J., assignor, by
mesne assignments, to Shellmar Products Com-
pany, Chicago, Ill., a corporation of Delaware

Application May 2, 1930, Serial No. 449,310
Renewed July 22, 1933

4 Claims. (Cl. 101—152)

This invention relates to an improved method and apparatus for use in the printing of webs, or continuous lengths of material.

In my co-pending application for Method of web printing, Serial No. 449,309, I have described and claimed a method making use of inks of different types to accomplish certain results. In my co-pending application for Rotary printing assembly, Serial No. 449,308, I have described and 10 claimed the construction of a printing assembly adapted to print on a continuous web a multiplicity of fac-similes with pre-determined spacing. Said machine having elements adjustable to permit a variation in the spacing of the fac- 15 similes on the web.

This application describes and claims the combination of the several elements enumerated plus such additional elements as are necessary to obtain, in a commercial way, the results de- 20 sired.

In particular, an object of my invention is to provide a machine to print material, like cellophane, now in use to wrap a great variety of merchandise. This material as ordinarily used 25 is transparent, very thin and not adapted to be handled in sheets over sheet fed printing presses.

A specific object of my invention is to provide a machine capable of printing a moving web of material with primary designs and immediately 30 thereafter printing other designs directly on said primary designs.

I prefer the machine to operate as follows: A primary design is printed on the web with pre-determined spacing, dependent upon the use to 35 which the printed material is to be put. After receiving the primary design the web is passed through a series of additional printing assemblies whereby further designs may be printed on the web, a part or all of which may be printed di- 40 rectly on the primary design. Each printing assembly will apply one color ink, or equivalent substance, and may, if desired, emboss the web as well.

After the web has been completely printed it 45 may be slit into narrow widths and passes over rollers positioned to lengthen the travel of the printed web, and thus provide additional time for drying or setting of the inks before the web is wound on a roll to any desired length.

50 In order to provide the proper tension on the web at all times I provide a novel arrangement of feed rolls capable of being adjusted for both great and small differences in web speed, resulting from changes in diameters of plate cylinders.

55 In carrying out my invention I prefer to use

a combination of printing assemblies adapted to print the primary design by means of gravure, or intaglio printing, and print the additional designs by means of typographical or relief print- 60 ing.

In order to use the same plate and impression cylinders and at the same time provide for changes in the length of web covered at each revolution of the said cylinders, I provide a novel arrangement for changing the effective diam- 65 eters of the plate and impression cylinders. The same gearing is used to drive the cylinders at all times, and the same inking mechanism is likewise used at all times.

In order to illustrate my invention reference is 70 had to the drawing in which like reference numerals represent like parts.

Fig. 1 is a general view of a preferred form of machine used to carry out my invention.

Fig. 2 is an end view of a portion of one of the 75 printing assemblies, showing the manner in which the same gearing is used to drive various diameters of plate and impression cylinders.

Referring to Fig. 1, reference numeral 4 is the 80 web of material being printed on. 5 is the frame of the machine. A supply roll 6 of material to be printed is supported at one end of the machine.

Mounted on the frame 5 is the printing assem- 85 bly 7 preferably of the gravure type and comprises a plate cylinder 8 and an impression cylinder 9. Contacting with the plate cylinder 8 is the coating roll 10 operating in the fountain 11. The scraper 12 removes the surplus ink or lacquer from the gravure plate.

Mounted on the frame 5 are the printing as- 90 sembles 13, 14 and 15. Each of these assemblies comprises a plate cylinder 16, an impression cylinder 17, an ink fountain 18 and the usual complement of oscillating, vibrating and distributing rolls necessary to ink the printing plates.

Mounted on the frame 5 is the slitting assem- 95 bly 19 for use if it is desired to slit the web into narrower strips, such as are required for cigar wrapping machines. A series of feed rolls 20 are provided to maintain the proper tension on the 100 web. The rollers 21, 22, 23 and 24 are used to permit looping of the web and drying of the inks before winding on the roll 25.

A blower 26 is provided to assist in cooling and 105 drying the ink forming the primary design.

Power is applied to the shaft 27, and through the gears 28 the impression cylinders 17 and 9 are rotated.

The friction wheel 29 are driven from the shaft 110 27 and serve to drive the slitting assembly 19 and

the feed roll assembly 20 though the friction discs 30. It is obvious that moving the friction wheels 29 towards or away from the center of the discs 30 will increase or decrease the speed of 5 the assemblies, and in this manner take care of variations in the amount of movement of the web for each revolution of the plate cylinders, with various diameters, which may be used.

Referring to Fig. 2, 16 is the plate cylinder 10 and 17 is the impression cylinder. A spur gear 31 is fixed to the impression cylinder. Meshing with this first gear 31 at all times, is a second gear 32, mounted on a stud 33 supported in the frame of the machine. A third gear 34 is positioned to be always in mesh with the second gear 32 and with a fourth gear 35 which is fixed to the plate cylinder and rotates therewith. The third gear is supported on a stud 36 which also serves to join the two swinging arms 37 and 38. The 15 outer end of the arm 38 being mounted to rotate about the axis of the gear 32 and the outer end of the arm 37 being mounted to rotate about the axis of the plate cylinder 16, and gear 35.

By this gearing arrangement it will be noted 20 that the plate cylinder will be driven with its axis in any of its positions, and since the gears 31 and 35 have the same number of teeth, the plate and impression cylinders will always be rotated the same number of revolutions per minute.

30. I claim:

1. The combination in a web printing machine, 35 of a printing assembly adapted to operate with various diameters of plate and impression cylinders, rolls for feeding said web to maintain the proper tension thereon, means for slitting said

web, and means for varying the speed of said web feeding rolls and said web slitting means to compensate for the variation in movement of said web which results when said cylinder diameters are varied.

2. The combination in a web printing machine, 80 of a printing assembly adapted to operate with various diameters of plate and impression cylinders, rolls for feeding said web to maintain the proper tension thereon, means for slitting said web, and adjustable driving means for said web feeding rolls and said web slitting means, whereby the variation in movement of said web which results when said cylinder diameters are varied may be compensated for.

3. The combination in a web printing machine, 85 of a printing assembly adapted to operate with various diameters of plate and impression cylinders, rolls for feeding said web to maintain the proper tension thereon, means for slitting said web, and adjustable friction driving means for said web feeding rolls and said web slitting means, whereby the variation in movement of said web which results when said cylinder diameters are varied may be compensated for.

4. The combination in a web printing machine, 90 of a printing assembly adapted to operate with various diameters of plate and impression cylinders, means for slitting said web, and means for varying the speed of said web slitting means to 100 compensate for the variation in movement of said web which results when said cylinder diameters are varied.

MAX STOESSEL.
